ROLLING MACHINE

Frank M. Kratoville, St. Louis, and Firmin M. Cunningham, Maplewood, Mo., assignors to James R. Kearney Corporation, St. Louis, Mo., a corporation of Missouri

Application January 24, 1946, Serial No. 643,177

8 Claims. (Cl. 140—113)

1

This invention relates generally to pressure rolling machines, and more specifically to pressure rolling machines which are adapted for use in connecting fittings to wires, cables, and other elongated bodies, and which includes pressure rollers that are rotated in contact with sleeve portions associated with said fittings in a manner to compress the sleeve portions and force the walls thereof into intimate, gripping contact with portions of the elongated bodies disposed within said sleeve portions so as to securely connect said elongated bodies and fittings together, the predominant object of the invention being to provide such a rolling machine which includes improved carriage means for movably supporting an elongated body and a fitting, which are to be connected, during rolling operation of the rolling machine.

Fig. 1 is a front elevation of a rolling machine constructed and arranged in accordance with this invention, portions of the operating handles of the machine, which actuate the rollers thereof intermittently, being broken away.

Fig. 2 is a vertical section taken on line 2—2 of Fig. 1.

Fig. 3 is a vertical section taken on line 3—3 of Fig. 2.

Fig. 4 illustrates a plurality of socket elements of different sizes and constructions which are employed in the use of the machine illustrated in Figs. 1, 2, and 3.

Fig. 5 is an enlarged section taken on line 5—5 of Fig. 1.

Fig. 6 is a fragmentary end elevation of the structure illustrated in Fig. 5, looking toward the left-hand end thereof.

Fig. 7 is a fragmentary end elevation of the opposite end of the structure shown in Fig. 5, a portion of the supported work being shown in section.

Fig. 8 is a fragmentary vertical section taken on line 8—8 of Fig. 5.

Fig. 9 is a view, partly in section and partly in elevation, illustrating the improved carriage means for supporting work being acted on by the machine.

Fig. 10 is a front elevation of the rolling machine, with the handles broken away, and showing the positions of the rollers when the work to be acted on by the machine is introduced into place for operation of the machine.

Fig. 11 is a view similar to Fig. 10, but showing the positions of the rollers of the machine at the commencement of a rolling operation of the machine.

2

Fig. 12 is a view similar to Figs. 10 and 11, but showing the positions of the rollers of the machine at the finish of a rolling operation of the machine.

Fig. 13 is a view similar to Figs. 10, 11 and 12, but showing the machine provided with rollers of a different type and illustrating the work acted on by said rollers.

Fig. 14 is a front elevation of a different type of machine which is provided with a crank for rotating the rollers thereof continuously, and which is constructed in accordance with the present invention.

Fig. 15 is a view partly in side elevation and partly in vertical section of the machine illustrated in Fig. 14.

Fig. 16 is a rear elevation of the machine illustrated in Figs. 14 and 15 with a part thereof shown in section.

Fig. 17 is an enlarged, fragmentary section taken on line 17—17 of Fig. 14.

Fig. 18 is a section taken on line 18—18 of Fig. 17 and looking in the direction of the arrow.

Fig. 19 is a section taken on line 19—19 of Fig. 17.

Fig. 20 is a view similar to Fig. 17, but illustrating an adapter employed when work of a different type is being acted on by the machine.

In the drawings, wherein are shown for purposes of illustration, merely, two embodiments of the invention, A designates generally in Figs. 1 to 13, inclusive, one form of the improved rolling machines disclosed herein. The rolling machine A includes a pair of spaced frame members 1 and 2 through which aligned upper openings 3 and 35 aligned lower openings 4 are formed, and arranged in these openings 3 and 4 are roller bearing assemblies 3' and 4' (Figs. 2).

The roller bearing assemblies 3' of the aligned openings 3 support for rotation an upper shaft 5, while the roller bearing assemblies 4' of the aligned openings 4 support for rotation a lower shaft 6. The shafts 5 and 6 have mounted on their forward portions a pair of pressure rollers 7 and 8, said pressure rollers being circumferentially grooved and being provided with recessed portions 7' and 8' which are adapted to perform a function to be hereinafter set forth.

The pressure rollers 7 and 8 are secured to the shafts 5 and 6 by keys 9 (Fig. 1), and said shafts 5 and 6 have secured to their forward faces disks 10 which are of greater diameter than the shafts so that they overlap the center openings of the rollers in which the forward end portions of the shafts are disposed. Fixedly mounted on the rear end portions of the shafts 5 and 6 is a pair of gear wheels 11 (Fig. 2) which are arranged in

50 55

mesh so as to insure uniformity of rotation of said shafts, a casing 12 being provided which is secured to the frame member 2 and houses the gear wheels 11.

In order to impart intermittent rotary movement to the rollers 7 and 8 clutch mechanisms 13 and 14 are employed, the clutch mechanism 13 being associated with the upper shaft 5 and the clutch mechanism 14 being associated with the lower shaft 6 (see Figs. 2 and 3). The clutches 13 and 14 are preferably of the over-running type and the central portions of the shafts 5 and 6 are shaped as shown in Fig. 3 to provide parts of said over-running clutches, said central portion of each of said shafts 5 and 6 being provided with a plurality of pairs of angularly related faces 15 and 16, and annular clutch elements 17 being arranged in embracing relation with respect to said central portions of said shafts 5 and 6. Spaces 18 are provided between the angularly related pairs of faces of the central portions of the shafts 5 and 6 and portions of the inner faces of the annular clutch elements 17, rollers 19 being disposed in these openings and said rollers being urged by coil springs 20 toward the narrower portions of said spaces. The annular, clutch elements 17 are provided with gear teeth 17' which extend over portions only of the circumferential faces of said annular, clutch elements and the gear teeth of the clutch elements are in mesh, as is shown in Fig. 3. The annular, clutch elements are subjected to rotation by a pair of handles 21 and 22 which are supported for pivotal movement by pivot elements 23 and 24 that are supported by the frame members 1 and 2, the handle 21 being provided with gear teeth 25 which mesh with the gear teeth 17' of the annular clutch element 17 which is associated with the upper shaft 5, while the handle 22 is provided with like gear teeth 25 which mesh with the gear teeth 17' of the annular clutch element 17 that is associated with the lower shaft 6.

The operation of an over-running clutch is well known and therefore need not be described in detail herein, it being sufficient for the purpose of this disclosure to say that when the handles 21 and 22 are moved toward each other the annular, clutch elements 17 are moved in the directions indicated by the arrows in Fig. 3, because of the meshing gear teeth of the handles and the respective annular, clutch elements. During such rotation of the annular, clutch members the rollers 19 are moved toward the portions of the spaces 18 which are of reduced width with the result that binding action takes place between said rollers and the faces 15 and the portions of the inner faces of the annular, clutch elements 17, whereby rotary motion is imparted to the shafts 5 and 6. Likewise, when the handles 21 and 22 are moved away from each other, the rollers 19 of the clutch mechanisms 13 and 14 are moved toward the portions of the spaces 18 which are of greater width, hence, no binding action takes place and the annular, clutch elements 17 rotate relative to the central portions of the shafts 5 and 6 without imparting rotary motion to said shafts. It will be noted that the rollers 19 of the clutch mechanisms 13 and 14 are retained in place, insofar as longitudinal movement of said rollers are concerned, by spacers 26 which are interposed between said clutch mechanisms and the frame members 1 and 2 (Fig. 2). Also, the handle 22 is provided with an extension 22' at its upper end which supports a pin 27 (Fig. 3) that contacts with the frame

5 member 2 to limit outward movement of the handles 21 and 22.

The general structure illustrated in Figs. 1 to 13, inclusive, and which has thus far been described in detail herein, is disclosed in United States Letters Patent No. 2,039,635, granted on May 5, 1936, to Ellis W. Cooper. The present invention relates particularly to a carriage structure which is adapted to support work being acted on by such a rolling machine and this carriage structure will now be described.

Extended outwardly from the frame member 1 of the rolling machine A is a pair of spaced posts 28 (Fig. 5) which are provided at their outer ends with enlarged head portions 29, said head portions being shaped in end elevation as is shown in Figs. 6 and 7. The head portions of the posts 28 are each provided with a seat 30 that is provided with divergent walls, one of which wall is of less length than the other wall, and said seats of said heads of said spaced posts are aligned with each other. Supported by the head portions 29 of the spaced posts 28 is a horizontal bar 31 of rectangular cross-section shape which is supported in the seats 30 of said head portions in the manner shown to good advantage in Figs. 6, 7, and 8. Associated with the heads 29 of the spaced posts 28 is a structure which comprises a pair of plate portions 32 that are joined by an integral extension 33. The plate portions 32 are secured to the heads of the posts by pairs of fastening devices 34 that extend through openings formed through flange portions 32' of said plate portions and which are screwed into screw-threaded openings formed in corresponding flange portions 29' forming parts of the heads 29. The plate portions 32 are shaped in cross-section as shown in Figs. 6, 7, and 8, said plate portions being provided with seats 35 that are shaped in accordance with the seats 30 of the head portions 29 of the posts 28, but which are reversed relative to said seats 30, said seats 30 and 35 of each related post head 29 and plate portion 32 combining to provide a partially rectangular guideway in which the bar 31 is confined for sliding movement longitudinally of the axis of said bar, and from which a portion of said bar extends in a downward direction (Fig. 2).

The means for securing the spaced posts 28, and the parts associated therewith, to the frame member 1, comprises bolts 36 (Fig. 8) which extend through aligned openings formed through the flange portions 32' of the plate portions 32 and through the posts 28, said bolts being provided with enlarged, knurled, head portions 36' that engage the forward faces of said flange portions 32', and said bolts 36 being provided with screw-threaded opposite end portions that are screwed into screw-threaded openings formed in the frame member 1. Because of this arrangement the entire work-supporting carriage may be removed from the rolling machine as an assembled unit, it being necessary to remove the bolts 36 to remove from the machine the unitary assembly made up of the posts 28, the structure of which the plate portions 32 form parts, and the slidably movable bar 31.

Secured to the slidably movable bar 31 at one end thereof is a member 37 which comprises a cylindrical portion 37a from which a flange portion 37b extends. The flange portion 37b of the member 37 is fixed to the bar 31 by securing elements 38, said flange portion being disposed horizontally, as is shown in Fig. 2, and the axis 70 75 of said cylindrical portion being aligned with the

bite of the pressure rollers of the rolling machine. The cylindrical portion 37a of the member 37 supports an appropriate socket element 39, one such socket element comprising a shank portion that is disposed in the opening of said cylindrical portion, and an enlarged head portion which abuts against an end face of said cylindrical portion 37a. The socket element 39 has formed therethrough an opening 40, said opening being of tapered shape throughout the portion thereof that extends through the head portion of the socket element, straight throughout a substantial portion of the shank portion of said socket element, and tapered at the outer end of said shank portion, as is shown in Fig. 5.

An outer portion of the shank portion of the socket element 39 extends outwardly beyond an end of the cylindrical portion of the member 37, and this extended shank portion has formed in the outer surface of the wall thereof an annular groove 41 that receives a portion of a retaining element 42. The retaining element is made of wire, or other suitable resilient material, an arcuate portion of said retaining element being seated in the lower portion of the groove 41 of the socket element 39, and an offset end portion of said retaining element being extended into an opening formed in the member 37 at the point designated by the reference character 42a so that said retaining element is supported for pivotal movement. Also, the retaining element is provided with an eye 42b which provides a grip. The portion of the retaining element which is disposed in the groove 41 of the shank of the socket element extends outwardly beyond the outer surface of said shank portion and thus retains the socket element in association with the member 37 so that it may not be accidentally displaced therefrom, and when it is desired to remove the socket element from the member 37 it is necessary, merely, to spring the arcuate portion of the retaining element laterally out of the groove of the socket element and move the socket element in the proper direction to withdraw the shank portion thereof from the cylindrical portion of the member 37.

Mounted at the end of the bar 31 opposite to the end thereof at which the member 37 is located, is a work-supporting structure 43. The work-supporting structure 43 comprises a pair of strips of resilient metal or other suitable material 43a and 43b, which are shaped as is shown in Fig. 7. The strips of material 43a and 43b are secured by fastening elements 44 to a block 45 which in turn is secured by fastening elements 45' to the bar 31. As is shown to good advantage in Fig. 7, the strip of material 43a is provided with a curved end portion 46 having an extension 46' projected therefrom, and the strip of material 43b includes a resilient finger 47 which extends into said curved end portion of said strip of material 43a, said finger being slightly curved at its end as indicated by the reference character 47'. The strip of material 43b is provided with an angularly projected portion 48, said projected portion 48 being adapted to engage a fixed abutment element 49, which is secured by fastening elements 49' to a portion of the structure of which the plate portions 32 form parts, so as to limit movement of the bar 31 during operation of the rolling machine.

The rolling machine illustrated in Figs. 1 to 12, inclusive, is adapted for use, particularly, in securing to end portions of cables, single strand elements, and other elongated bodies, end fit-

tings which are adapted for various purposes. In Figs. 10, 11, and 12, which illustrate the operation of the improved rolling machine, the work illustrated as being acted on by the rolling machine comprises an end fitting B which includes an integral, thin-walled sleeve C into which is projected throughout substantially the entire length thereof an end portion of a cable or other elongated element D. In the use of the rolling machine A of the present invention, attachment of the end fitting B to the elongated element D is accomplished by compressing the wall of the sleeve into tight, gripping contact with the portion of the elongated element located within said sleeve, through rolling pressure exerted by the rollers of the machine against said wall of said sleeve. In the use of the improved rolling machine the handles 21 and 22 of the machine A are operated to bring the recessed portions 7 and 8 of the rollers 7 and 8 to the approximate positions in which they are shown in Fig. 10, or said rollers may be adjusted to such positions by hand, and with the recessed portions of the rollers so positioned the work to be acted on by the machine may be readily introduced into place with respect to the movable work carriage of the machine. In introducing the work into place with respect to the work carriage the end fitting B is seated in the forward, tapered portion of the opening 40 formed through the socket element 39 (see Fig. 5) and the elongated element D is forced into position within the work-supporting member 43 where a portion of said elongated element is gripped between the free end portion of the resilient finger 47 of said work-supporting member and a portion of the curved end portion 46 thereof.

With the work thus securely supported by the movable work carriage of the machine, the movable work carriage is moved to the position in which it is shown in Fig. 11, and the handles of the machine are actuated to rotate the rollers 7 and 8 intermittently. As the rollers 7 and 8 are rotated by actuation of the handles of the machine they will engage the sleeve C of the work at the inner end thereof, as is shown in Fig. 11, and continuation of the intermittent rotation of the rollers will cause the wall of the sleeve to be compressed into tight gripping contact with the portion of the elongated element D which is disposed within said sleeve. Also, as the wall of the sleeve C is being compressed on the end portion of the elongated element D by the rollers 7 and 8 of the machine, the work, and the entire movable work carriage by which the work is supported, will move to the left in Fig. 11, the bar 31 moving longitudinally of its supports provided by the posts 28 and the parts associated therewith. Thus, the work is securely supported by the work carriage throughout the entire rolling operation of the machine, and when the rolling operation has been completed the rollers may be rotated by hand to again bring the recessed portions of the rollers to the positions they occupy in Fig. 10, whereupon the work may be removed from the work carriage. In order to facilitate such rotation of the rollers 7 and 8 by hand the roller 8 is provided with a pair of outwardly extended pins 50 which provide finger grips.

In Fig. 4 are shown three different types of the socket members which are adapted for association with the member 37 that is carried by the bar 31 of the work carriage of the rolling machine A, and when a particular type of work is

to be acted on by the rolling machine the appropriate socket element is applied to the member 37. The socket element 39, that is shown in section in Fig. 5 and which is illustrated at the top of Fig. 4, is used with an end fitting of the type illustrated by dotted lines in Fig. 5, the latter type of end fitting abutting against the tapered wall of the opening 40 of the socket element which is of reduced size and is located at the left-hand end of the socket element 39, as illustrated in Fig. 5. The intermediate socket element 39a shown in Fig. 4 is employed with an end fitting of the general type illustrated by full lines in Fig. 5 but which is of a smaller size, while the lowermost socket element 39b is employed with end fittings of the types illustrated by full lines and dotted lines in Fig. 9, an end fitting of the type shown by full lines in Fig. 9 abutting against the wall of the larger, outward tapered portion 39c of the opening through the socket element, while the type of end fitting shown by dotted lines in Fig. 9 abuts against the wall of the inner and smaller tapered portion 39d of the opening through said socket element 39b.

In Fig. 13 a rolling machine is illustrated which is provided with rollers of a type different from that of the rollers shown in Figs. 10, 11, and 12. The rollers 51 and 52 are adapted for use in securing to a cable D', or other elongated element, abutment elements E at points intermediate the ends thereof. The particular type of abutment element E shown in Fig. 13 comprises a substantially spherical center portion with integral sleeve portions extending outwardly from opposite sides of said spherical portion, and said abutment member is slipped onto the cable from an end thereof. The rollers 51 and 52 are so shaped that portions of said rollers rotate in contact with the sleeve portions of the abutment element E so as to compress them into close, gripping contact with portions of the cable D'. When a cable D' is to have an abutment element E applied thereto with the aid of the rolling machine illustrated in Fig. 13, the cable is gripped by the work-supporting structure 43, heretofore described herein, and therefore the work is supported by the movable work carriage of the machine for proper application of pressure by the rollers of the machine to the abutment element E.

In Figs. 14 to 20, inclusive, a type of rolling machine is illustrated which is provided with pressure rollers that are particularly adapted for continuous rotation during a rolling operation of the machine, although said pressure rollers may be operated intermittently if desired. The machine illustrated by Figs. 14 to 20, inclusive, comprises a supporting frame having a pair of frame members 53 and 54 which support for rotation an upper shaft 55 and a lower shaft 56, said shafts having fixedly mounted thereon at their forward ends a pair of pressure rollers 57 and 58 which are provided with opposed recessed portions 57' and 58' (Fig. 14). The means for subjecting the shafts 55 and 56 and the pressure rollers 57 and 58 to rotation comprises a hand crank 59 which is mounted, through the instrumentality of an overrunning clutch 59', on a shaft 60 that is supported by the frame members 53 and 54, there being a pinion 61 also mounted on said shaft 60 which meshes with a gear wheel 62. The gear wheel 62 is mounted on a shaft 63 that is supported for rotation by the frame members 53 and 54, and this shaft 63 has fixed thereto a pinion 64 which meshes with a gear wheel 65 that is fixedly mounted on the

shaft 56, said gear wheel being arranged in mesh with a similar gear wheel 65' which is fixedly mounted on the shaft 55. It is obvious in view of the gearing just described that rotation of the hand crank 59 in the direction indicated by the arrow in Fig. 16 will cause the pressure rollers 57 and 58 to rotate at the proper speed in the directions indicated by the arrows in Fig. 14.

Formed in the forward face of the frame member 53 is a dove-tail groove 66 (Fig. 15) which extends horizontally, said groove having set therein a bar 67 of dove-tail cross-sectional shape which is supported by the walls of the groove 66 for movement longitudinally of its axis. Secured to the forward face of the frame member 53 is a plate 68 which is of the shape shown in Fig. 14, said plate being secured in place by suitable fastening devices 69 so that it covers a substantial portion of the dove-tail groove 66. The plate 68 is provided with a slot 69 formed therein which is open at an end of the plate (Fig. 14). Secured to the bar 67 at one end thereof is a cylindrical socket element 70 whose axis is aligned with the bite of the pressure rollers 57 and 58, said socket element having an opening 71 formed longitudinally therethrough which is of tapered formation throughout a portion of its length, as indicated at 71a, and which is stepped throughout the remainder of its length to provide opening portions of varying diameters, as indicated at 71b. The cylindrical socket element 70 is secured to the bar 67 by a pair of fastening elements 72 which pass through openings in a narrow spacer 73 and are screwed into screwthreaded openings formed in the socket element, said spacer being of such width that it will pass into the slot 69 of the plate 68. At the end of the bar 67 opposite to the end thereof at which the socket element 70 is mounted thereon, a work supporting structure 74 is provided, said work supporting structure comprising a pair of elements 74a and 74b formed of strips of resilient material which are secured by fastening elements 75 to a block 76 that is secured by fastening elements 77 to the bar 67. The resilient elements 74a and 74b are shaped in side elevation as is shown in Fig. 18; that is to say, portions of said elements extend outwardly from the block 76 and are bent toward each other at their forward ends, with inner gripping portions 74c and 74d extending rearwardly from said outer, bent portions. The rearwardly extended gripping portion 74d of the work-supporting structure 74 is provided with an upwardly bent abutment element 74e which serves to limit inward movement, relative to the gripping portions 74c and 74d, of work being applied to said work-supporting structure.

In the use of the rolling machine illustrated in Figs. 14 to 20, inclusive, the rollers 57 and 58 are adjusted to position recessed portions 57' and 58' of said rollers so that the work to be acted on by the machine may be applied to the work carriage of the machine. The end fitting F of the work is then introduced into the tapered portion 71a of the opening 71 of the socket element 70 in contact with the wall thereof, and a portion of the elongated element G is forced between the gripping portions 74c and 74d of the work-supporting structure 74, an end portion of the elongated element G being disposed within the sleeve portion H of the end fitting F (see Fig. 17). The bar 67 is then moved to the right to properly position the sleeve portion H of the end fitting F with respect to the rollers, and the crank

arm is rotated to cause the pressure rollers to compress the wall of the sleeve portion of the end fitting into tight gripping contact with the portion of the elongated element G which is disposed within said sleeve portion. While the rolling operation is being performed the bar 67 moves with the work being acted on by the machine so as to properly support the work at all times during said rolling operation, and when the rolling operation has been completed the rollers are brought to a position where recessed portions 57' and 58' thereof will permit removal of the work from the work-supporting carriage of the machine. In this connection it is to be noted that a pivoted detent 78 (Fig. 16) is provided which is caused by a spring 79 to engage the teeth of the gear wheel 62 to prevent reverse movement of the pressure rollers and the gearing associated therewith. However, this detent has connected thereto an actuating element 80 which may be drawn outwardly to disengage the detent from the teeth of said gear wheel 62 if it is necessary to reverse the direction of rotation of the pressure rollers to properly position the recessed portions thereof for application of the work to, or removal of the work from, the work-supporting carriage of the machine.

The opening 11 of the cylindrical socket element 70 is shaped as shown in Fig. 17 so that it will receive end portions of fittings of various sizes and shapes. Also, an adapter 81 may be associated with the socket element 70, as is shown in Fig. 20, to provide for the reception of fittings of yet other types and sizes, said adapter being secured in place in association with the socket element 70 by a bolt 82.

We claim:

1. A pressure rolling machine comprising supporting frame means, a pair of pressure rollers supported for rotation by said frame means, means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work.

2. A pressure rolling machine comprising supporting frame means, a pair of pressure rollers supported for rotation by said frame means, means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work by frictionally gripping said portion of said work.

3. A pressure rolling machine comprising supporting frame means, a pair of pressure rollers supported for rotation by said frame means,

means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work, said work-holding member including resilient portions which frictionally grip said portion of said work.

4. A pressure rolling machine comprising supporting frame means, a pair of pressure rollers supported for rotation by said frame means, means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work, said opening of said socket element having portions shaped and proportioned to receive work end portions of different shapes and sizes.

5. A pressure rolling machine comprising supporting frame means, a pair of pressure rollers supported for rotation by said frame means, means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work, said opening of said socket element having portions shaped and proportioned to receive work end portions of different shapes and sizes, and an adapter arranged for association with said socket element and adapted to receive work end portions which because of their sizes or shapes are not receivable by said socket element.

6. A pressure rolling machine comprising supporting frame means, a pair of pressure rollers supported for rotation by said frame means, means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work by frictionally gripping said portion of said work.

opposite end of said bar which engages a portion of said work, said opening of said socket element having portions shaped and proportioned to receive work end portions of different shapes and sizes, an adapter arranged for association with said socket element and adapted to receive work end portions which because of their sizes or shapes are not receivable by said socket element, and means for securing said adapter in place with respect to said socket element.

7. A pressure rolling machine comprising supporting frame means, a pair of pressure rollers supported for rotation by said frame means, means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work, said carriage including means for removably supporting said socket element, and means for securing said socket element in position with respect to its supporting means.

8. A pressure rolling machine comprising supporting frame means, a pair of pressure rollers

supported for rotation by said frame means, means for subjecting said pressure rollers to rotary movement, and a carriage for supporting work acted on by said pressure rollers, said carriage comprising an elongated bar supported by said frame means for movement longitudinally of its axis with respect to said frame means, and spaced work-engaging means carried by said bar, said spaced work-engaging means including a socket element disposed adjacent to one end of said bar and having an opening formed therein which receives an end portion of said work, and a work-holding member disposed adjacent to the opposite end of said bar which engages a portion of said work, said carriage including means for removably supporting said socket element, and resiliently releasable means for securing said socket element in position with respect to its supporting means.
